(57) **CLAIM**

The ornamental design for a cleaning robot as shown and described.

DESCRIPTION

1.1 is a front view of a first embodiment of a cleaning robot;
1.2 is a back view thereof;
1.3 is a left view thereof;
1.4 is a right view thereof;
1.5 is a top view thereof;
1.6 is a bottom view thereof;
1.7 is a top perspective views thereof;
1.8 is a bottom perspective views thereof;
1.9 is an enlarged view of a part denoted and marked by broken lines in 1.7;
2.1 is a front view of a second embodiment of a cleaning robot;
2.2 is a back view thereof;
2.3 is a left view thereof;
2.4 is a right view thereof;
2.5 is a top view thereof;
2.6 is a bottom view thereof;
2.7 is a top perspective views thereof;
2.8 is a bottom perspective views thereof; and

(Continued)

2.9 is an enlarged view of a part denoted and marked by broken lines in **2.7**.

The broken lines in the reproductions **1.2** to **1.5** and **1.8** depict portions of the cleaning robot that form no part of the claimed design, and the broken lines in the reproductions **1.7**, **1.9**, **2.7** and **2.9** are used only for indication purpose and form no part of the claimed design.
